United States Patent Office

Des. 196,303
Patented Sept. 17, 1963

196,303

CONTROL STATION CABINET

Henry H. Bluhm, Phoenix, Ariz., assignor to General
Electric Company, a corporation of New York

Filed Aug. 11, 1961, Ser. No. 66,314

Term of patent 14 years

(Cl. D26—5)

FIG. 1

FIG. 2

FIG. 1 shows a front perspective view of a control station cabinet, showing my new design.

FIG. 2 is a rear perspective view of same.

The dominant features of my design reside in the portions shown in solid lines.

I claim:

The ornamental design for a control station cabinet, as shown and described.
